(57) **CLAIM**

The ornamental design for an embossed paper, as shown and described.

DESCRIPTION

FIG. 1 is a plan view of an embossed paper showing the design; and,

FIG. 2 is an enlarged fragmentary sectional view taken along line 2—2 in FIG. 1.

The four edges of the embossed paper have been shown broken away to indicate that it repeats indeterminately in all directions as well as to define one repeat unit of the design.
